(57) **CLAIM**

The ornamental design for a liquid detergent bottle dress cover, as shown and described.

DESCRIPTION

FIG. 1 is a front elevation view of a liquid detergent bottle dress cover showing my new design;

FIG. 2 is a rear elevation view thereof;

FIG. 3 is a left side elevation view thereof, the right side elevation view being a mirror image;

FIG. 4 is a top plan view thereof;

FIG. 5 is a bottom plan view thereof; and,

FIG. 6 is an isometric view thereof.

The broken lines shown in FIG. 6 are for illustrative purposes only and form no part of the claimed design.
